US00D897225S

(12) **United States Design Patent** (10) **Patent No.:** **US D897,225 S**
Chapman et al. (45) **Date of Patent:** **** Sep. 29, 2020**

(54) **SENSOR HOUSING**

(71) Applicant: **Topcon Positioning Systems, Inc.**,
Livermore, CA (US)

(72) Inventors: **Angus Chapman**, Brisbane (AU);
Reilly Edwards, Brisbane (AU)

(73) Assignee: **Topcon Positioning Systems, Inc.**,
Livermore, CA (US)

(**) Term: **15 Years**

(21) Appl. No.: **29/675,176**

(22) Filed: **Dec. 28, 2018**

(51) LOC (12) Cl. **10-04**

(52) U.S. Cl.

USPC **D10/65**

(57) **CLAIM**

The ornamental design for a sensor housing, as shown and
described.

DESCRIPTION

FIG. 1 is a front perspective view of a sensor housing
according to our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken lines shown in the drawings depict environment that forms no part of the claimed design.
